PURGE ARRANGEMENT FOR HEATING COILS

Milner Noble, Syracuse, N. Y., assignor to Aerofin Corporation, Syracuse, N. Y., a corporation of New Jersey

Application April 8, 1944, Serial No. 530,203

6 Claims. (Cl. 237—67)

1

This invention relates to heat exchange units and more particularly to methods of and means for purging such units.

The general object of the invention is to provide simple piping arrangements to serve single and multiple heating units for assuring effective withdrawal from the units of non-condensable gases whose presence in the units causes corrosion as well as losses in heat exchange efficiency.

A feature of the invention resides in the provision of an auxiliary pipe conduit or steam escape route, leading from the return header of a single heating coil housing a plurality of coils positioned in parallel flow arrangement between said return header and a steam supply header. The auxiliary pipe conduit follows a serpentine path along the face of the coil and serves effectively to withdraw from the coil non-condensable gases; such gases and steam withdrawn from the coil being discharged into a return line leading from the return header.

Another feature of the invention resides in routing a supply of steam to a plurality of coils, the steam flowing in series arrangement through the coils and in counterflow to that of air (or other gases) to be heated passing through the coils. The steam supply first enters the coil contacting the hottest air and then proceeds through the other coils, in series, until it reaches the coil which the entering air first contacts, provision being made in the course of steam travel between coils to assure continuous purging of each coil together with drainage of condensate therefrom. The course of steam flow in the piping arrangement, plus the provision for individual coil purging, assures purging of all coils regardless of their position with respect to the air passing in contact with all of the coils.

The features of the invention and the advantages in efficiency of operation resulting therefrom will be apparent from the following description of applicant's invention as applied to illustrative coil arrangements in which:

Fig. 1 is a diagrammatic representation of a single encased heating coil to which has been applied a piping layout in accordance with applicant's invention to assure purging of non-condensable gases to eliminate corrosion in the coil, and

Fig. 2 is a diagrammatic view of a plurality of encased coils served by another form of applicant's invention for accomplishing the same purpose.

Considering the drawings, similar designations referring to similar parts, numeral 3 represents

2

a conditioner housing forming the casing of a fan blast system. In such systems, it is usual to have outdoor air, either alone or in combination with return air, the proportions thereof being regulated by hand controlled or automatically controlled dampers, the air entering the housing to be heated by one or more coils positioned within the housing. A fan or blower delivers the heated air through a series of ducts to one or more enclosures to be heated. In connection with the apparatus shown in Fig. 1, the air intake and discharge arrangements are not shown since they are well known in the art and form no part of this invention.

15 Conditioner housing 3 has upper and lower enclosing elements 4 and 5 as well as sides 6 made of sheet metal or the like so that air pulled by fan 7 will necessarily pass through encased heating coil 8 which is confined within housing 3.

20 Heating coil 8 comprises a casing 9 within which are suitably supported supply header 10 and return header 11. Steam from a source of supply, such as a boiler, is admitted through feed line 12 to supply header 10. Heating surface, 25 preferably in the form of a plurality of finned tubes 13, connect the supply header to the return header. One such tube is shown in Fig. 1, but it will be understood that in practice a number of such tubes connect the headers together,

30 the tubes being positioned closely together so that the air pulled by fan 7 will effectively be heated by contact with tubes 13, with the bypassing factor held to a specified minimum. Return line 14 is connected to return header 11 by connecting line 15. Clean-out portion 16 is provided at the lower end of line 15 so that flow substantially free of solid matter will take place from line 15 into line 14.

35 As is common in such systems, air and other non-condensable gases enter the tubes comprising the heating surface with the result that unless such non-condensable gases are eliminated corrosion takes place within the tubes and efficiency in heat exchange is reduced.

40 To assure effective purging, applicant provides purge line 17 leading from return header 11 preferably having a body portion in the form of a serpentine secondary relief coil 18 positioned adjacent the face of heating coil 8 in the path of the flow of air entering housing 3. Coil 18 connects to return line 14 by means of line 19 provided with a clean-out 20 similar to 16. Trap 21 is provided at the discharge sides of lines 15 and 19 before they connect to return line 14.

45 The provision of secondary coil 18 provides a

condenser or air relief coil separate from the heating coil. The connection of this secondary coil to return header 11 assures complete purging of all air and non-condensable gases which are forced into the secondary coil. Since the cold air stream pulled by the fan first strikes the secondary coil, the condensing action therein is effective and the pressure of steam from header 11 is sufficient to keep this coil clean. The result is an active passage of condensate and non-condensables from the secondary to the return line, thereby assuring complete purging of the tubes of the heating coil 8.

In Fig. 2 a plurality of coils 8A, 8B, 8C, and 8D are positioned within conditioner housing 3 and the air pulled by fan 7 passes through the series of heating coils in the direction shown by the arrow. In this arrangement, steam from feed line 12 first enters the supply header of coil 8D leaving from the return header thereof through discharge line 23D. Condensate will flow from discharge line 23D to return line 14, trap 24D being interposed in the usual manner. However, the steam leaving the return header at the bottom of coil 8D will flow through line 25D to the supply header of coil 8C. This steam and condensate will leave the return header of coil 8C flowing through discharge line 23C. The condensate will flow to discharge line 14 through trap 24C but the steam will go through line 25C to coil 8B where the action will be repeated with the steam flowing from the supply header to the return header of coil 8B and leaving through discharge line 23B. The condensate from line 23B flows to return line 14 through trap 24B and the steam goes through line 25B to the last coil 8A. The steam passes from the supply header to the return header of coil 8A; and the condensate and steam flow from discharge line 23A through trap 24A to return line 14. Air vent 26 connects to discharge line 23A.

The coldest air first enters coil 8A where the steam pressure is least and where the mean effective difference between the heating surface and the air is greatest. This is conducive to effective condensation in coil 8A with the result that purging will be assured in this coil where it is most required. The non-condensables in the first three coils will either leave through discharge lines 23D, 23C, and 23B or enter coil 8A. The effective condensing action in coil 8A assures relief of the non-condensables from this coil. The steam pressure is adequate to achieve such purging in view of the effective condensing action. Air vent 26 connected to discharge line 23A aids relief of air from the system.

The piping arrangements of Figs. 1 and 2 assure complete purging by removal of non-condensable gases from the greater portion of heat exchange surface and by providing effective condensing action either in auxiliary coil or in a small portion of the surface used in a multiple coil arrangement from which the gases are effectively delivered.

I claim:

1. A method of purging a steam heating coil which consists in admitting steam to a supply header, passing steam from the supply header through a plurality of tubes to a return header, withdrawing condensate from the return header directly to a return line, passing steam and non-condensable gases from the return header through a secondary coil disposed adjacent the steam coil to condense the steam, returning the condensate to a return line, and passing air to be heated

first through the secondary coil and then through the steam coil whereby condensation in the secondary coil serves effectively to withdraw non-condensable gases from the steam coil.

5 2. A method of purging a series of heating coils which consists in admitting steam from a source of supply to the supply header of a first steam coil, routing the steam downwardly through tubes of the first steam coil to a second header, routing 10 condensate from the second header to a return line while routing the steam from the second header to the supply header of a second steam coil, said steps being repeated for each coil employed in the series except the last coil, purging 15 non-condensable gases from the last coil, removing condensate from the last coil to the return line, and passing air in contact with the coils in a direction from the last to the first coil whereby the coldest air contacts the coil wherein the steam pressure is least to bring about effective condensation in the last coil to assure purging of non-condensable gases from the heating coil and to induce flow of non-condensable gases through the other coils.

20 3. A piping arrangement for assuring purging of non-condensable gases from a steam heating coil comprising a supply header, a return header, a plurality of tubes connecting the supply header and the return header, a steam supply line leading to the supply header, a return line leading from the return header, a secondary gas relief coil disposed adjacent the finned tubes of the steam heating coil, a line connecting the return header to the entrance end of said relief coil, 25 means connecting the discharge end of the relief coil to the return line, and means for passing air to be heated first through the relief coil and then through the heating coil to effect condensation in the relief coil to purge non-condensable gases from the heating coil.

40 4. A piping arrangement for assuring purging of non-condensable gases from a plurality of steam heating coils which comprises a series of coils, each coil having a supply header and a return header connected by a series of tubes, a steam supply line connected to the supply header of the first coil of the series, similar pipes connecting each return header of a preceding coil to a supply header of a succeeding coil, the last coil of the series serving as a gas relief coil, a return line connected to the return headers, and means for passing air to be heated first through the relief coil and then through the remaining coils to effect condensation in the relief coil to purge non-condensable gases from the coils.

45 5. A piping arrangement for purging non-condensable gases from a steam heating coil including a coil having a supply header and a return header, means for supplying steam to the supply header, a return line, a connecting line having a trap device therein and connecting said return header and return line, a purge line connected to said trap device and connecting said return header and return line, said purge line having a portion 50 thereof positioned in the path of an air stream passing through the coil.

60 6. In apparatus of the character described, the combination of a casing, a steam heating coil in said casing, said coil including a supply header connected to a source of supply of steam, a return header, and a plurality of tubes connecting the supply and return headers, a secondary coil in the casing disposed adjacent the tubes of the heating coil, a line connecting the return header with the entrance end of the secondary coil, a

return line, a third line connecting the return header with the return line to permit condensate to pass to the return line, a trap in the third line, a line connecting the secondary coil with the third line at a point up stream from said trap to permit condensate from the secondary coil to pass to the return line, and a fan in said casing adapted to pass air to be heated first through the secondary coil and then through the heating coil to effect condensation in the secondary coil thereby purging non-condensable gases from the heating coil.
